UNITED STATES PATENT OFFICE.

EPHRAIM HAMBUJER, OF DETROIT, MICHIGAN, ASSIGNOR OF ONE-HALF TO
S. WIGHTMAN STEWART, OF SAME PLACE.

STORE-SERVICE APPARATUS.

SPECIFICATION forming part of Letters Patent No. 374,062, dated November 29, 1887.

Application filed August 8, 1887. Serial No. 246,376. (No model.)

To all whom it may concern:

Be it known that I, EPHRAIM HAMBUJER, a citizen of the United States, residing at Detroit, in the county of Wayne and State of Michigan, have invented certain new and useful Improvements in Store-Service Apparatus, of which the following is a specification, reference being had therein to the accompanying drawings.

10. This invention relates to new and useful improvements in store-service apparatus or cash-carriers; and the invention consists in the peculiar construction and arrangement of the motor and carrier, all as more fully hereinafter described.

15. In the drawings which accompany this specification, Figure 1 is a perspective view of the motor, and Fig. 2 is a vertical central section of the motor and carrier.

20. A is a hanger, to which is secured in any suitable manner one end of the single-wire track B.

25. C is a cross-bar secured by clamping, by means of a similar cross-bar or otherwise, to the hanger A. Projecting horizontally from this cross-bar and secured thereto are two parallel guide-rods, D, upon which are sleeved the springs E. To the free end of these guide-rods D is adjustably secured a cross-head, F, 30 to which is centrally hinged the catch G, the free end of which terminates in a wedge-shaped incline.

35. H is a lever fulcrumed at I in any suitable manner upon the hanger A, and with its free end projecting downward in suitable proximity to the floor, to be operated therefrom. The upper end of this lever is adapted to engage with the catch G, as shown in Fig. 2, and by moving the lever in the proper direction 40 the catch G strikes the stop J, which has an incline, K, suitably constructed to release the catch from its engagement with the lever. Then the cross-head will be shot forward by the tension of the springs.

45. The carrier consists of the top L, preferably made of metal, in which are secured the rollers M to guide the carrier on the wire track. To the lower end of this top is detachably secured in any suitable manner the usual receptacle, N, for the reception of the cash, and by means of the arm O, detachably secured to the top of the carrier, a basket, P, of any suitable

description, may be carried along with the carrier.

Q is a yoke secured to the cross-head F, and this yoke has attached to it two clamping-springs, R, so arranged that when the carrier is propelled against it the springs R and yoke Q will embrace the top of the carrier and hold it against any accidental displacement, except when the carrier is propelled by the reaction of the springs E, as before explained; and a suitable spring, T, may be arranged to spring the lever H into its normal position after its actuation, and the braces V are arranged to hold the hanger A in a firm position.

What I claim as my invention is—

1. In a store-service apparatus, the combination, with a hanger, of a cross-bar secured thereon, laterally-projecting guide-rods on said cross-bar, coil-springs sleeved upon said guide-rods, a cross-head adapted to slide upon said guide-rods and to be reciprocated thereon, a catch centrally hinged to said cross-head, a lever adapted to engage with said catch, and a stop adapted to release the lever from engagement with the catch, substantially as described.

2. In a store-service apparatus, the combination of a spring-motor consisting, essentially, of two springs sleeved upon guide-rods, a cross-head movable upon said guide-rods and provided with spring-jaws, a lever adapted to move said cross-head and thereby compress the springs, a single-wire track, and a catch upon said track adapted to automatically disengage the lever and cross-head, as and for the purpose specified.

3. In a store-service apparatus, the combination, with the hanger and the track B, secured at one end thereto, of the stop J on said track and having an incline, K, a spring-pressed cross-head, a catch, G, carried thereby, and a lever fulcrumed on the hanger and engaging said catch, substantially as and for the purpose specified.

In testimony whereof I affix my signature, in presence of two witnesses, this 28th day of July, 1887.

EPHRAIM HAMBUJER.
